CLAIM

The ornamental design for a container lid, as shown and described.

DESCRIPTION

FIG. 1 is a top, front, and right perspective view of a container lid showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, rear, and left perspective view thereof; and, FIG. 9 is a top, front, and right perspective view thereof, showing the container lid attached to an exemplary container.

The broken lines in the figures represent portions of the container lid and environment, which form no part of the claimed design.
